UNITED STATES PATENT OFFICE.

JOHN W. BROWN, OF BROOKLYN, NEW YORK.

APPARATUS FOR DRYING MALT.

SPECIFICATION forming part of Letters Patent No. 277,876, dated May 22, 1883.

Application filed September 12, 1882. (No model.)

To all whom it may concern:

Be it known that I, JOHN W. BROWN, of Brooklyn, county of Kings, and State of New York, a citizen of the United States, have invented an Improved Apparatus for Drying Brewery Grain or Malt, of which the following is a full, clear, and exact description, reference being had to the accompanying drawings, forming part of this specification.

10 My invention relates to the drying of the grains or malt of brewers as the same comes from the mash-tubs, for the purpose of improving the condition of said grain or malt as food for cattle and stock; and my invention consists in the improved apparatus hereinafter described for drying the said grain or malt, composed of a grain or malt chamber closed from the air, and having a perforated bottom, beneath which is a chamber for heating air, 20 together with an air-exhaust apparatus leading from the upper part of said malt-chamber, all as specified.

Figure 1 is a side view of an apparatus embodying my invention, the walls being partly 25 cut away to disclose the interior mechanism. Fig. 2 is a plan of the lower or air-heating chamber, showing the steam-coil; and Fig. 3 is a section of the steam-coil, together with its drip-roof or guard.

30 A is a tub or vat having the continuous walls a , the solid bottom a' , and the lid a'' , which is capable of being hermetically closed, or substantially so. Within this tub is arranged the false bottom B, placed more or less 35 above the solid bottom a' . Two chambers are thus constituted within the tub, the large upper chamber, C, and the lower smaller chamber, C'. The false bottom or partition is perforated, as shown.

40 Within the upper chamber, C, is arranged a stirring apparatus, which may be in the form shown—namely, a fixed bevel-gear mounted rigidly on a stud, as at d , at the center of the lower part of the chamber C, with which gear engage the bevel-pinion d' , one of which is on each of the shafts d^2 , carrying the stirring-arm d^3 . The shafts d^2 are hung in a frame, d^4 , and the frame and shafts are rotated by means of a vertical shaft, d^5 , which extends above the lid of 50 the tub. The frame and shafts being rotated within the tub by the driving-shaft d^5 , the pin-

ions d' , running on the gear d , will operate to rotate the shafts d^2 axially, and thus to revolve the arms d^3 , and these latter will agitate and stir the contents of the chamber C. I do not 55 claim the said stirring devices as new, nor do I limit myself to the use of the same. Any other devices which will effectively agitate the contents of the chamber C may be employed.

Within the chamber C', and preferably elevated somewhat above the floor thereof, I arrange the steam heating-coil E. In the side walls of said chamber I provide openings and air-valves, (shown at e .) Over the upper exposed surface of the piping composing the steam-coil I preferably place the drip-roofs e' , the same being composed of a strip of angle metal with its apex arranged to project vertically above the line of the pipe, and with its longitudinal edges extending downward about 70 the sides of the piping. By means of this drip-roof any moisture which finds its way through the perforated bottom will be prevented from falling upon the hot coil, and thus injuring the same, but will fall upon the roofing e' , and pass down the same and fall to the bottom of the chamber C' between the pipes. 75

Opening out of the top or upper part of the chamber C is the air-conduit F, leading to an air-exhaust fan or pump, F'.

80 The operation of my apparatus is as follows: The steam-coil, being heated, warms to a high degree the lower chamber, C'. In the upper chamber, C, is then placed a quantity of wet brewers' grain as the same comes from the mash-tubs. Power is then applied to the exhaust-fan F', and also to the stirring device, and at the same time the air-valves e are opened. The external air admitted through inlet c is heated in the chamber C' and passes up through 85 the perforated bottom B into the upper chamber, C, being drawn into said chamber through the mass of the grain, and passes out at F and through the fan. At the same time the grain is continuously agitated by the stirring devices. 90

95 All the conditions essential for the successful and effectual drying of wet and hot brewery grain or malt are thus provided for in my apparatus, and such grain or malt thus dried is greatly improved and enhances in value as an article of food for cattle and other live stock. 100

What I claim as my invention, and desire to secure by Letters Patent, is—

In an apparatus for drying brewery grain or malt, having an upper or grain chamber, C, provided with a stirring device, an exhaust-conduit, F, and fan F', and a lower or air-heating chamber, C', with the intermediate perforated partition, B, the combination, with the

steam heating-coil E in said lower chamber, of the angular roofing-strips e', arranged above to the line of the piping of the coil, as described, and for the purpose specified.

JOHN W. BROWN.
